UNITED STATES PATENT OFFICE.

FREDERICK H. HALSTEAD, OF WORCESTER, MASSACHUSETTS, ASSIGNOR TO RIVETT LATHE AND GRINDER COMPANY, OF FANEUIL, MASSACHUSETTS, A CORPORATION OF MASSACHUSETTS.

GRINDER.

1,299,713.

Specification of Letters Patent.

Patented Apr. 8, 1919.

Application filed March 7, 1917. Serial No. 153,192.

To all whom it may concern:

Be it known that I, FREDERICK H. HALSTEAD, a citizen of the United States, and a resident of Worcester, county of Worcester, 5 and State of Massachusetts, have invented an Improvement in Grinders, of which the following description, in connection with the accompanying drawings, is a specification, like characters on the drawings representing like parts.

This invention pertains to improvements in grinders and, more particularly, though not exclusively, to improvements in mechanisms for relatively feeding together the 15 grinding wheel and the work and mechanisms for separating the work and tool for inspection and gaging of the work, or other purposes.

In the illustrative embodiment of a preferred construction of my invention shown 20 in the drawings, and herein specifically described, I have shown a grinder adapted for the grinding of ball races, and resembling somewhat the oscillating grinder shown 25 in my copending application, Serial No. 130,062, filed November 7, 1916.

In grinding mechanisms, it is the best practice where possible to actuate the feeding movement at the end of a relative traverse of the work and tool, and preferably 30 when the work and tool are out of contact with each other. In grinding mechanisms providing for automatic relative traverse of work and tool, and automatic feeding movement, this has heretofore necessitated separate adjustment of the periods of reversal of relative traverse and of the periods at 35 which feeding movement is actuated. It is among the purposes of the present invention to provide reversing mechanism and automatic feeding mechanism which are automatically, relatively timed so that a change in the position or period of reversal automatically correspondingly changes the 40 time of feeding movement, thus rendering unnecessary separate adjustment of the timing mechanism for timing the reversal of relative traverse of work and tool, and of the timing mechanism for timing the actuation of the feeding movement.

Another object of the present invention is to provide an automatic feeding mechanism for automatically and intermittently relatively feeding together the work and tool in

gradually reducing amounts, so that the 55 cut is started with a relatively heavy cut which is gradually reduced until a very fine finishing cut is provided to finish the work, thus effecting a great saving in machine time over machines having an automatic, constant feed throughout the grinding operation.

Another object of the invention is to provide an improved construction for relatively separating the work and tool in a direction 60 transverse to the feeding movement without disturbing the feed slide or its automatic connections.

Other objects and advantages of the invention will appear in the following descriptive matter.

In the drawings which show an illustrative embodiment of one form of my invention,

Figure 1 is a side elevation, partially 75 broken away, of an illustrative grinding machine embodying a preferred form and application of my invention.

Fig. 2 is a partial, vertical section, partly 80 in elevation on the line 2—2 of Fig. 1, and shows a detail of a portion of the preferred feed mechanism selected to illustrate one phase of my invention.

Fig. 3 is a vertical section, partly in elevation on the line 3—3 of Fig. 2.

Fig. 4 is a top plan view of the parts shown in Figs. 2 and 3.

Fig. 5 is a plan of a detail of the reversing and feed actuating mechanisms shown in Fig. 1, and will be fully described herein- 90 after.

Fig. 1 of the drawings shows a ball race grinder having a chuck 9, holding the work 10, and mounted on the work spindle 11, rotated in bearings 12 by a belt (not shown) 95 on the pulley 13.

The work spindle bearings 12 and parts carried thereby are shown mounted on an oscillatory support 14, carried by a pivotal shaft 15 which is preferably oscillated by alternate engagement of worms 16—17 with opposite sides of the worm gear 18, as best shown in Fig. 5. The worms 16—17 are preferably carried by the shiftable cage 19, preferably actuated by mechanism which is 100 fully described in my copending application above mentioned. The grinding wheel 20 is carried by a rotatable tool spindle 21

running in a bearing 22, which as shown can be fed transversely of the machine, to feed the tool into the work. The before described parts are all similar to those shown 5 in my copending application and require no detailed description. They constitute one form of grinding machine wherein the work and tool are relatively traversed and reversed by alternately engaged, oppositely 10 effective driving elements and wherein relative feeding movement is provided.

Referring to those features of my invention which differ from my copending application, I have shown the cross feed slide 15 23, carrying the work spindle bearing 22 and associated parts. The longitudinal slide 24 is preferably as shown, carried by the transverse feed slide. Feeding movement is preferably imparted to the parts carried 20 by the feed slide through a screw shaft 25, which may be of the usual construction shown in my copending application, and preferably carrying a gear 26, driven by a pinion 27 on the ratchet shaft 28 which carries the 25 ratchet 29. Step by step rotation is preferably imparted to the ratchet 29 by a pawl 30, carried by the reciprocatory rod 31 to which, as best shown in Fig. 3, reciprocatory movement is imparted in one direction by a 30 cam 32, and preferably yieldingly actuated in the opposite direction as by the spring 33. The cam 32 is preferably moved by shifting of the reversing mechanism, and to this end I have shown it carried by an arm 34, projecting from the shifting worm cage 19 (Fig. 5). Thus, whenever the cage 19 is shifted, preferably by mechanism shown in my copending application, the arm 34 will pass under the rod 31, pushing the latter upwardly and imparting movement to the pawl 30. If desired, the pawl 30 may be reversible as shown, so that feeding movement may be imparted by said pawl and coöperate with a double ratchet, as shown in my 40 45 copending application, thereby imparting feeding movement in either direction to the parts carried by the feed slide, depending on whether the pawl turns its coöperating ratchet on its upward or downward stroke. 50 For the purposes of this application it is immaterial whether the shifting, reversing mechanism impart ratchet turning movement to the pawl or whether it compresses the spring which imparts ratchet turning movement to the pawl.

To regulate the amount of feed, I preferably provide means for manually varying the effective throw of the cam 32, and to this end I have shown the thumb nut 35, 60 preferably knurled on the outside and having a female thread on the inside, engaging a male thread on a sleeve 36, which is preferably held non-rotatably relative to the rod 31 by a pin 37 passing through a slot 38 65 in the casing 39. Rotation of the nut 35

will thus impart longitudinal movement to the sleeve 36 and the rod 31, thereby varying the point to which the rod 31 will be returned by the spring 33 and hence varying the effective portion of the cam 32.

I preferably provide means for automatically and gradually decreasing the feed and to this end I preferably provide a ratchet 40 forming a part of the thumb nut and engaged by a pawl 41, preferably actuated by the reversing mechanism and carried by the arm 34, and pressed by a spring 45 against the ratchet 40, which it is adapted to turn in one direction only—viz., the direction which will impart feed decreasing 80 movement to the rod 31. Thus the feed is progressively decreased until the rod 31 is elevated above the cam 32, at which point the feed will stop though the machine may continue to run, thereby reciprocating the 85 cam 32. To prevent jamming of the mechanism actuated by the pawl 41, in case the machine is left running for too long a period, I proportion the threads on the nut 35 and sleeve 36, so that they will "run out" 90 at the point where the rod 31 ceases to be engaged by the cam 32.

Any suitable means may be provided for discontinuing or throwing out of gear the automatic feed reducing mechanism but I 95 prefer to provide as shown means for withholding the pawl 41 from engagement with the ratchet 40, typified by the pin 47 in the slot 48 and adapted to be caught in a locking portion 49 of the slot 48.

The longitudinal slide 24, carried by the cross slide 23 may coöperate with any suitable positioning means, such as the usual latches and stops for accurately determining the position of the tool during the grinding 105 operation.

Any of the usual lever mechanisms may be provided to facilitate the movement of the tool carrying head on the longitudinal slide. By locating the feed slide below the longitudinal slide I am enabled to greatly increase the bearing surface of the feed slide, which is necessarily free during the grinding operation while the longitudinal slide is preferably locked. I am also enabled to leave all parts of the cross feed mechanism stationary while the tool is withdrawn from the work.

The operation of the specific embodiment of my invention, illustrated in the drawings, 120 is as follows:

The tappets carried by the oscillatory support 14 (identical with those shown in my copending application) are set to engage the reversing pin 50 at the desired points of reversal, but preferably when the work 10 and tool 20 are out of contact. The shifting of the reversing pin through mechanism like that shown and described in my copending application shifts the worm carry- 130

ing cage 19 alternately from one side to the other at the time when reversal is to take place. The cam 32 being carried by the arm 34 necessarily is moved at the same time, thereby imparting feeding movement through the rod 31, pawl 30, ratchet 29, pinion 27 and gear 26 to the screw shaft 25 which effects the cross feed of the tool into the work. When the automatic feed 10 reducing pawl 41 is in position to engage the ratchet 40 it imparts, at every movement of the arm 34 in one direction, a partial rotation to the nut 35, thereby progressively reducing the extent to which the rod 15 31 is permitted to engage the cam 32, and therefore gradually reducing the feeding movement.

While I have shown in the drawings and have described for illustrative purposes a 20 preferred construction of one embodiment of my invention, I wish it understood that my invention is not limited to the embodiment shown and described, but that major changes involving omission, substitution, 25 alteration and re-arrangement of parts and functions may be made without departing from the scope of my invention, which is best defined in the following claims.

Claims:

30 1. A grinder comprising in combination an abrasive tool; work rotating means; tool rotating means; traversing means for traversing said tool and the work, one relative to the other; reversing means for said traversing means including two oppositely effective, driving elements, and shifting means providing for alternate engagement of said driving elements; and feeding means actuated by shifting movement of said shifting 40 means.

2. A grinder comprising in combination an abrasive tool; traversing means for traversing said tool and the work one relative to the other; reversing means for said traversing means, including two oppositely effective driving elements and shifting means providing for alternate engagement of said driving elements; and automatic feeding means, the operation of which is timed by 50 and coincident with the operation of said reversing means.

3. A grinder comprising in combination an abrasive tool; traversing means for traversing said tool and the work, one relative to the other; reversing means for said traversing means, providing for change of the points of reversal; feeding means; and automatic timing means insuring substantial coincidence of operation of said reversing 60 means and said feeding means when the points of reversal of said reversing means are changed.

4. A grinder comprising in combination an abrasive tool; traversing means for traversing said tool and the work, one relative

to the other; reversing means for said traversing means including tappet means adjustable to change the points of reversal; feeding means; and actuating means for said feeding means, automatically timed by 70 said tappet means to provide substantial coincidence of reversal and feed.

5. An oscillating ball race grinder, comprising in combination a work support; an abrasive tool; automatic means for oscillating said work support to traverse the work relative to the tool, including two oppositely effective driving elements; automatic reversing means providing for alternate engagement of said driving elements; and automatic feeding means actuated by said automatic reversing means and providing for feed of the tool toward the work substantially coincident with the operation of said automatic reversing means. 85

6. An oscillating grinder comprising in combination a work support carried by an oscillatory support, a worm gear operatively connected to said oscillatory support, two worms, a shifting cage carrying said forms 90 for alternate engagement with said worm gear, and feed mechanism actuated by shifting movement of said shifting support.

7. A grinder comprising in combination a rotating tool spindle; a rotating work spindle; and feed means for shifting one of said spindles relative to the other, including a ratchet, a pawl for said ratchet, a cam for imparting ratchet turning movement to said pawl and manually operable means for varying the movement imparted to said pawl by said cam. 95

8. A grinder comprising in combination a rotating tool spindle; a rotating work spindle; and feed means for shifting one of said spindles relative to the other and including a ratchet 29, a pawl 30, a rod 31, and a cam 32, having a to and fro movement for imparting movement to said rod 31 and said pawl 30. 105

9. A grinder comprising in combination a rotating tool spindle; a rotating work spindle; traversing means for imparting traversing movement to the work and tool, one relative to the other; reversing means for 110 said traversing means, including two oppositely effective driving elements, and shifting means 19 carrying said driving elements; and feed means for shifting one of said spindles relative to the other, said feed 115 means including a cam 32, moved to and fro by shifting of said shifting means 19, a rod 31, reciprocated in at least one direction by said cam 32, and ratchet and pawl means actuated by reciprocation of said rod 31. 120

10. A grinder comprising in combination work rotating means; tool rotating means; and feed means including a ratchet, a pawl, means for imparting to and fro movement to said pawl and means automatically and 130

gradually decreasing the extent of to and fro movement of said pawl as feeding movement progresses.

11. A grinder comprising in combination 5 work rotating means; tool rotating means; and feed means including a ratchet, a pawl, a cam for imparting to and fro movement to said pawl and means for automatically gradually decreasing the effective throw of 10 said cam, whereby the to and fro movements of said pawl are automatically gradually decreased in extent as feeding progresses.

12. A grinder comprising in combination work rotating means; tool rotating means; 15 traversing means for traversing the tool and work, one relative to the other; reversing means for said traversing means including two oppositely effective driving elements; and feeding means actuated by shifting 20 movement of said shifting means and having a pawl 41 engaging a ratchet 40, operatively connected to means for reducing the rate of feeding movement as feeding movement progresses.

13. An automatic ball race grinder comprising in combination an oscillatory work support; a frame, a cross feed slide carried by said frame, a longitudinal slide carried by said cross slide, and a work spindle carried by said longitudinal slide, automatic 30 cross feeding means coöperating with said cross feed slide to feed said tool spindle in a direction transverse to its axis, said longitudinal slide providing for separation of the work and tool without movement of said 35 cross feed slide.

14. A grinder comprising in combination a rotating work spindle; a rotating tool spindle; and feeding means, including a shifting cam, a coöperating spring pressed element, a pawl operatively connected to said spring pressed element, a ratchet engaging said pawl and means operated by said ratchet for shifting one of said spindles relative to the other. 40

In testimony whereof, I have signed my name to this specification.

FREDERICK H. HALSTEAD.
